POCKET TOOL

John D. Olt, Sierra Madre, Calif., assignor to Pacific Handy Cutter, Incorporated, El Monte, Calif.

Filed Nov. 16, 1970, Ser. No. 25,984

Term of patent 14 years

Int. Cl. D8—05

U.S. Cl. D87—8.3

FIG. 1 is a perspective view of a pocket tool showing my new design;

FIG. 2 is a front elevational view of the tool shown in FIG. 1;

FIG. 3 is a side elevational view of the tool shown in FIG. 2;

FIG. 4 is an end elevational view taken in the direction shown in FIG. 2;

FIG. 5 is a rear elevational view of the tool shown in FIG. 2;

FIG. 6 is a sectional view taken along the plane 6—6 of FIG. 2.

The broken line disclosure of a conventional chain is shown in FIG. 1 for illustrative purposes only.

I claim:

The ornamental design for a pocket tool, as shown and described.
